UNITED STATES PATENT OFFICE.

GEORGE FREDERICK JACKSON, OF BLACKBURN, ENGLAND.

AIR-MOISTENING APPARATUS.

Application filed January 21, 1918. Serial No. 212,979.

To all whom it may concern:

Be it known that I, GEORGE FREDERICK JACKSON, a subject of the King of Great Britain, and resident of Ridgeholme, Ravenswing Avenue, Blackburn, in the county of Lancaster, England, have invented a certain new and useful Improvement in Air-Moistening Apparatus, of which the following description, having reference to the accompanying sheet of drawings, is a specification.

It relates to apparatus for use in the moistening or humidifying of air and distributing same in rooms, workshops, weaving sheds and other places (or for humidifying by other liquids than water, as liquid hydrocarbons, desired to be used for other purposes) of the type or character comprising a main passage or conduit within a cavity of which is situated or mounted devices for spraying or atomizing water (or other liquids) through which spray of water or liquid, air is forced by a fan or other air propelling mechanism, said air being caused to travel through the spray to gather same up and carry it along through the conduit from which it is delivered by lateral nozzles extending from said main conduit as is well understood.

In connection with this type of apparatus I have often found that some of the moisture in the issuing humidified air accumulates at the orifices of the nozzles to such an extent as to form drops which fall therefrom in a most undesirable manner.

To produce means whereby said condensed moisture is prevented from accumulating and descending or falling to any undesirable place, but is caught and returned to a suitable receptacle from which it is either again used in the apparatus or is otherwise dealt with so that the objectionable features heretofore experienced are entirely avoided; is the object of my present invention.

In the accompanying sheets of drawings which are illustrative of my invention:—

Fig. 1 is a side elevation illustrating the type of apparatus to which my invention relates, the same being shown as mounted in a room and extending from a side wall C thereof in manner well known.

Fig. 2 is a plan of certain of the parts shown by Fig. 1, and shows the nozzles with

my improved devices mounted thereon. 55 One of said nozzles and the parts that I mount thereon in accordance with my invention is shown in section.

Fig. 3 is a sectional end elevation of the main passage or conduit showing one of 60 the nozzles in section and the other in elevation with my improved devices mounted thereon as hereinafter explained, the said figure being drawn to an enlarged scale.

Fig. 4 is a sectional plan illustrating my 65 improved device in detail, the same being drawn to an enlarged scale.

Fig. 5 is a sectional end elevation showing a modified form of my improved device.

Fig. 6 is a side elevation of certain of the parts shown by Fig. 1 but with a modified form of my improved device mounted thereon.

A indicates the main passage or conduit 75 through or along which the humidified air is propelled, said conduit being mounted usually in the upper part of a room with the propelling fan B situated near one or other of the walls C of said room, while through the 80 pipes 2 and 3 are admitted water or other liquid and steam or compressed air or the like which are controlled by the valves 2^a and 3^a respectively.

To attain the object of my invention I 85 mount or arrange over each of the lateral projecting nozzles 4 an additional sleeve 5 which will reach slightly beyond the outer orifice or end 4^a of the nozzle 4 thus any moisture which may gather and fall in 90 the form of drops from the end of said nozzle 4 is received by said outer sleeve 5. This said moisture is conducted by said outer sleeve 5 down a trough or guiding passage 6 into a gutter 7 which is preferably situated beneath the main conduit A so that said gutter 7 is common to the whole series of sleeves 5, this gutter 7 conducts the accumulated moisture back to a receptacle 8.

In order to enable the moisture which is received by the outer sleeves 5 to be guided in its passage from said sleeve 5 into the passage 6 I fix ridges 9, 9^a within said sleeve 5 so that by having same shaped to 105 be at a greater distance towards the outer end 4^a of the inner conduit 4 approaching each other when reaching towards the wall

of the main conduit A the moisture is thereby conducted into the passage 6 from which it falls into the main or common gutter 7 as hereinbefore described.

5 Although I have hereinbefore described my invention as consisting of a sleeve 5 which encircles the entire length of each nozzle 4 it is perfectly obvious that said sleeve may surround only the outer end of 10 the nozzle as shown at 5^a in Fig. 5 in which case the passage 6 would be continued beneath the nozzle 4 from the part 5^a to the main gutter 7. Or again the sleeve 5 may be divided so as to only cover the lower 15 portion of the nozzle 4 as illustrated by Fig. 6. However I find that the sleeve in its entirety answers the purpose better and therefore I preferably make use of the same.

Such being the nature and object of my 20 said invention what I claim is:—

In apparatus of the class to which this invention relates, a main conduit, a fan casing to which said conduit is connected, a fan mounted in said casing, a pipe for 25 conducting liquid to the main conduit, another pipe for conducting fluid or gas under pressure to said main conduit independently of the fan, discharge nozzles opening from the walls of said conduit, a shield 30 surrounding and extending beyond the outer end of each nozzle and spaced therefrom to form a passage between said shield and said nozzle, a main gutter below the main conduit, a trough leading from each 35 shield to the main gutter, and a receptacle into which the main gutter discharges.

GEORGE FREDERICK JACKSON.
